UNITED STATES PATENT OFFICE.

WILLIAM WESLEY WISE, IRA IVAN COOPER, AND WILLIAM L. MILLER,
OF EVANS CITY, PENNSYLVANIA.

NUT-LOCK.

SPECIFICATION forming part of Letters Patent No. 788,981, dated May 2, 1905.

Application filed September 27, 1904. Serial No. 226,200.

To all whom it may concern:

Be it known that we, WILLIAM WESLEY WISE, IRA IVAN COOPER, and WILLIAM L. MILLER, citizens of the United States, residing at 5 Evans City, in the county of Butler, State of Pennsylvania, have invented certain new and useful Improvements in Nut-Locks; and we do hereby declare the following to be a full, clear, and exact description of the invention, such as 10 will enable others skilled in the art to which it appertains to make and use the same.

This invention relates to nut-locks, one object being to provide an exceedingly simple, inexpensive, durable, and efficient means to 15 prevent loosening of the lock occasioned by jar or otherwise.

Another object of the invention resides in locking the bolt and nut against accidental loosening or separation through the instrumentality of a peculiarly-shaped key formed 20 of a single piece of material.

With these and other objects in view the present invention consists in the combination and arrangement of parts, as will be herein- 25 after more fully described, shown in the accompanying drawings, and particularly pointed out in the appended claim, it being understood that changes in the form, proportion, size, and minor details may be made within 30 the scope of the claims without departing from the spirit or sacrificing any of the advantages of the present invention.

In the drawings forming a portion of this specification, and in which like numerals of reference indicate similar parts in the several views, Figure 1 is a perspective view of the invention. Fig. 2 is a longitudinal sectional view of the same, and Fig. 3 is a detail perspective view of the locking-key.

Referring now more particularly to the accompanying drawings, the reference character 1 designates a bolt of ordinary form, having its screw-threaded end 2 slotted or bifurcated longitudinally, as indicated by the character 3. The nut 4 has its outer face serrated at intervals, as at 5, for a purpose presently explained, and this nut is provided with the usual screw-threaded bore, whereby it may

have a working fit upon the bolt, as well understood. By reason of the slotted or bifurcated end of the bolt the screw-threaded end has a tendency to spread outwardly, causing the screw-threads thereof to bite into and bind against the screw-threaded bore of the nut. This binding action in itself acts in a measure 55 to prevent loosening of the nut; but in order to secure a positive locking engagement of the two elements—the bolt and nut—a wedge-shaped key, having one of its sides serrated or otherwise roughened, as at 6, is driven into 60 the slot or bifurcation 3, spreading the free end of the bolt into tight engagement with the threads of the bore of the nut, the serrations on the side of the key serving to bite into one wall of the slot or bifurcation 3 and prevent 65 accidental displacement of the former. As clearly shown in the drawings, the key is not only of a wedge, but is also of a T, outline, the head 7 thereof being integral with its shank portion 8. In other words, it will be 70 seen that the T-shaped key is formed of a single piece of material.

In the use of railroad-rails much inconvenience and annoyance beside the wrecking of the rolling-stock has been occasioned by the 75 weight and jarring caused by the latter in its movements over the rails to loosen the nuts and bolts, and therefore the present invention is particularly adapted for this specific purpose. For instance, when the bolt 1 80 is passed through the rail in the usual manner and the nut 2 is screwed upon the bolt until it has reached the side of the rail or the usual fish-plate, the rail and fish-plate being not shown, it is only necessary to drive the 85 present peculiarly-formed wedge into the bifurcated end of the bolt until the integral head portion 7 of the wedge fits in corresponding serrations or the like, upon the opposite sides of the bore of the nut, the serrations or teeth 6 of the key engaging one of the walls of the bifurcation and preventing 90 accidental displacement of the key. It is obvious, therefore, that when the key is positioned as explained the nut cannot turn upon 95 the bolt or the bolt with respect to the nut.

What is claimed is—

A nut-lock, comprising a bolt having one of its ends screw-threaded and bifurcated, a screw-threaded nut having a working fit upon the screw-threaded end of the bolt, said nut having one of its faces roughened, and a T-shaped wedge fitting in said bifurcation with the head portion thereof registering with the roughened surface of the nut, the wedge having one side of its shank portion provided with teeth for engagement with one wall of the said bifurcation to prevent accidental

withdrawal of the key therefrom, the head and shank portion of the key being formed of a single piece of material.

In testimony whereof we affix our signatures in presence of two witnesses.

WILLIAM WESLEY WISE.

IRA IVAN COOPER.

WILLIAM L. MILLER.
